FOUNDRIES, OF CHICAGO, ILLINOIS, A CORPORATION OF NEW JERSEY.

INTEGRAL BRAKE-BEAM.

1,290,160.

Specification of Letters Patent.

Patented Jan. 7, 1919.

Application filed June 23, 1917. Serial No. 176,546.

To all whom it may concern:

Be it known that I, WILLIAM E. FOWLER, Jr., a citizen of the United States, and resident of Chicago, in the county of Cook and State of Illinois, have invented certain new and useful Improvements in Integral Brake-Beams, of which the following is a specification.

My invention relates to brake beams for railway cars and more particularly to a novel integrally formed or cast brake beam.

One of the objects of this invention is to secure in a brake beam the greatest possible efficiency with a given weight of metal.

Another object is to provide a simple brake beam adapted to meet the various requirements for successful commercial operation.

These and other objects are accomplished by providing a metal brake beam comprising a body portion of uniform section formed of a horizontal web and vertical flanges, and trunnions integral with said body portion at its opposite ends.

The invention is illustrated on the accompanying sheet of drawings, in which,

Figure 1 is a plan view of a brake beam constructed in accordance with my invention;

Fig. 2 is an edge view of the same, and

Fig. 3 is a sectional view taken in the plane of line 3—3 of Fig. 1.

For accomplishing the objects of this invention, it is found that a beam of substantially I-shape in section serves best. For this reason I have shown in the drawings a beam of I-shape in cross section, the beam having a horizontal web 10 and vertical flanges 11 and 12. The brake beam is of uniform sec-

tion, and has intermediate its ends apertured portions 13 in the web to which the force applying means may be operatively connected. This beam is an integral structure, preferably cast, trunnions 14 being cast or formed integral with the body portion at its opposite ends. In this particular case the trunnions are shown as having a peripheral groove 15, by means of which an adjustable brake head of a common form may be mounted thereon.

It is apparent that various forms of trunnions may be provided on the ends of the beam without departure from my invention, and it is my intention to cover broadly the idea of providing a metal brake beam comprising a body of uniform cross section formed of a horizontal web and vertical flanges, and trunnions integral with said body portion at its opposite ends.

I claim:

1. A metal brake beam comprising a body portion of uniform section formed of a horizontal web and vertical flanges, and trunnions integral with said body portion at its opposite ends.

2. A metal brake beam comprising a body portion of uniform I-section, having a horizontal web and vertical flanges, and trunnions integral with said body portion at its opposite ends.

Signed at South Whitley, Indiana, this 20th day of June, 1917.

WILLIAM E. FOWLER, JR.
